CLAIM

The ornamental design for the goggle lens, as shown and described.

DESCRIPTION

FIG. 1 is a rear top, and right perspective view of the goggle lens illustrating the new design;

FIG. 2 is a front and right perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a front, left and top perspective view illustrating the goggle lens of FIGS. 1–8 assembled into a goggle;

FIG. 10 is a front elevational view thereof;

FIG. 11 is a rear elevational view thereof;

FIG. 12 is a right side elevational view thereof;

FIG. 13 is a left side elevational view thereof;

FIG. 14 is a top plan view thereof; and,

FIG. 15 is a bottom plan view thereof.

The dash-dash broken lines in the figures are shown for the purpose of illustrating portions of the goggle lens and environmental structure and form no part of the claimed design. The dash-dot broken lines define the bounds of the claimed design and form no part thereof.
